Primary Examiner — Holly H Baynham*(74) Attorney, Agent, or Firm* — Banner & Witcoff, Ltd.(57) CLAIM

The ornamental design for a bag, as shown and described.

DESCRIPTION

FIG. 1 is a top, front, left perspective view of a bag showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The even-length broken lines within the claimed areas represent stitching. The uneven-length broken lines depicting the remainder of the bag show features that form no part of the claimed design.

1 Claim, 6 Drawing Sheets(56)
